US0D1040763S

(12) **United States Design Patent** (10) Patent No.: **US D1,040,763 S**
(45) Date of Patent: ** Sep. 3, 2024

(54) **COIL COMPONENT**

(71) Applicant: **TDK Corporation**, Tokyo (JP)

(72) Inventors: **Nobuo Takagi**, Tokyo (JP); **Toshio Tomonari**, Tokyo (JP); **Setu Tsuchida**, Tsuruoka (JP); **Syun Ashizawa**, Tokyo (JP)

(73) Assignee: **TDK CORPORATION**, Tokyo (JP)

(**) Term: **15 Years**

(21) Appl. No.: **29/909,304**

(22) Filed: **Aug. 3, 2023**

Related U.S. Application Data

(62) Division of application No. 29/791,220, filed on Jan. 5, 2022, now Pat. No. Des. 997,877, which is a division of application No. 29/663,033, filed on Sep. 11, 2018, now Pat. No. Des. 942,946, which is a division of application No. 29/614,451, filed on Aug. 18, 2017, now Pat. No. Des. 831,570, which is a division of application No. 29/528,830, filed on Jun. 1, 2015, now Pat. No. Des. 798,814.

(57) **CLAIM**

The ornamental design for a coil component, as shown and described.

DESCRIPTION

FIG. 1 is a front view of a first embodiment of a coil component showing our new design;

FIG. 2 is a back view of the design shown in FIG. 1;

FIG. 3 is a left side view of the design shown in FIG. 1;

FIG. 4 is a top view of the design shown in FIG. 1;

FIG. 5 is a bottom view of the design shown in FIG. 1;

FIG. 6 is a perspective view of the design shown in FIG. 1;

FIG. 7 is a front view of a second embodiment of a coil component showing our new design;

FIG. 8 is a back view of the design shown in FIG. 7;

FIG. 9 is a left side view of the design shown in FIG. 7;

FIG. 10 is a top view of the design shown in FIG. 7;

FIG. 11 is a bottom view of the design shown in FIG. 7; and,

FIG. 12 is a perspective view of the design shown in FIG. 7.

A right side view of the design according to the first embodiment is symmetrical to FIG. 3, and is not illustrated. A right side view of the design according to the second embodiment is symmetrical to FIG. 9, and is not illustrated.

1 Claim, 8 Drawing Sheets
